UNITED STATES PATENT OFFICE.

JAMES MACKAYE, OF CAMBRIDGE, MASSACHUSETTS.

CENTRIFUGAL SEPARATING APPARATUS.

Application filed September 27, 1921. Serial No. 503,595.

To all whom it may concern:

Be it known that I, JAMES MACKAYE, a citizen of the United States, residing at Cambridge, in the county of Middlesex and State of Massachusetts, have invented certain new and useful Improvements in Centrifugal Separating Apparatus, of which the following is a specification.

This invention relates to centrifugal separators and more particularly to centrifugal separators designed for continuously separating solids from liquids. The invention is especially concerned with the problem of separating the solid and liquid constituents of slimes which are formed in certain processes involved in mining and ore reduction where a large volume of material must be handled and in which both the solid and liquid constituents, after separation, must be discharged from the apparatus while it continues to operate uninterruptedly.

In my co-pending application Serial No. 368,927, filed March 26, 1920, I have described and claimed a novel apparatus of this type. The present invention is concerned with an apparatus of the general character disclosed in my prior application, and it aims particularly to devise improved mechanism for controlling the discharge of the solid constituents from an apparatus of this general type, to improve the mechanism that levels or distributes the solid material within the separator, and generally to improve the operation, construction and organization of apparatus of this character. To these ends especially important features of the invention reside in a novel construction of rotary valve mechanism which controls the discharge of the solid material from the separator, and in a rotary mechanism for levelling or distributing this solid material within the separator.

Since the proportions of the solid and liquid constituents of the slimes above referred to vary within wide limits, it is necessary to vary the rate of removal of the solid material from the separator, and the present invention provides a novel arrangement whereby this result can be conveniently accomplished.

This and other objects of the invention and the manner in which it is here proposed to accomplish them will be readily understood from the following description, when

read in connection with the accompanying drawings, and the novel features will be particularly pointed out in the appended claims.

In the accompanying drawings illustrating the preferred embodiment of my invention,

Figure 1 is a side elevation;

Fig. 2 is a front elevation;

Fig. 3 is a cross sectional plan view on the line 3—3 of Fig. 1;

Fig. 4 is a vertical cross sectional view through the center of the machine, the top portion above the separator chamber being omitted;

Fig. 5 is an enlarged cross sectional detail view showing the construction and arrangement of the liquid outlet;

Fig. 6 is a fragmentary plan view showing the belt shifting mechanism;

Fig. 7 is a half plan of the interior valve plate;

Fig. 8 is a half plan of the bottom plate of the separation chamber; and

Fig. 9 is a half plan of the exterior valve plate.

The apparatus shown comprises a vertical shaft consisting of an upper hollow portion 11, and a lower solid portion 12, the two parts of the shaft being secured together in any suitable manner. This shaft rotates in upper and lower bearings 13 and 14, respectively, in the supporting frame 15. A pulley 16 fixed near the upper end of the shaft provides suitable means for connecting the same to a source of power.

The separator chamber comprises a cylinder 17, Fig. 4, having top and bottom plates 18 and 19, respectively, these plates being provided with flanges 20. The circular plates 18 and 19 are secured to the hollow portion 11 of the shaft and each plate is provided with a plurality of rectangular holes or valve ports 21 circumferentially arranged, as shown in Fig. 8, these holes 21 being radially bevelled at their inner and outer ends, as shown in Fig. 4, to assist the flow of the solid material therethrough. Baffle plates or partitions 22 and 23 of a diameter slightly less than the internal diameter of the cylinder 17 are securely mounted on the hollow portion 11 of the shaft and are spaced apart from the plates 18 and 19, respectively, this arrangement providing an annular passage for the flow

60

110

of the solid material and a chamber in which such solid material may collect.

Located between each pair of plates 18, 22 and 19, 23, is an interior valve plate 24 provided with an internal gear 26 and also provided with a plurality of radially extending arms 25 which form valves. The faces of the plates 24 engage the inner faces of the respective plates 18 and 19 and act, 10 when rotated, to alternately cover and uncover the rectangular holes or valve ports 21 in said plates 18 and 19. On the exterior of the plates 18 and 19 are mounted circular end plates or members 28 and 29, respectively, each of which is provided with a plurality of rectangular slots 30 circumferentially arranged, and equal in number to the number of valves 25 on the plates 24. Each of these members 28 and 29 is also provided with an internal gear 38, Fig. 9. The inner ends of these slots 30 are radially bevelled to register with the bevels of the corresponding ends of the valve ports 21 in the plate 18, as clearly shown in Fig. 4. These 20 slots 30 lead to upper and lower troughs, the upper trough 31 being shaped to guide the solid materials downward, while the lower trough 32, is shaped to direct the solid materials upwardly, both troughs discharging 25 the solid material on to a rotating discharge 30 platform 33. A flanged pulley 34 is formed integral with the member 29.

Connecting the baffle plates 22 and 23 are a plurality of tubes 35, preferably four in 35 number, and these tubes form housings for shafts 36, the ends of which are reduced in diameter beyond the ends of the tubes 35. On these reduced ends of each shaft 36 are secured pinions 37, two for each end of each 40 shaft, each pair being separated by the top and bottom plates 18 and 19 respectively. The inner pinions 37 mesh with the internal gears 26—26 in the plates 24—24, while the outer pinions mesh with the internal gears 45 38—38 of the members 28 and 29, and this mechanism drives the said plates 24 and members 28 and 29 in unison with but at a different speed from that of the cylinder 17.

The fluid mixture to be treated is led into 50 a tank 39 and thence into the hollow portion 11 of the shaft, the flow of liquid into this tank being regulated in any suitable manner, as by a valve controlled by a ball float. The liquid flows from the tank 39 into the hollow 55 portion 11 of the shaft by gravity, and through holes 40, Fig. 4, into the lower part of the cylinder 17. It is obvious that due to the rapid rotation of the cylinder, the solid particles of material carried by the liquid 60 will be thrown against the peripheral wall of the cylinder and after a time will build up a layer 41 of material hereinafter referred to as mud. The liquid, being lighter 65 than the solid material, will occupy the central portion of the cylinder and, due to

the hydraulic head upon it, will flow to the upper part of the cylinder, where it will be discharged through pipes 42. These pipes are led to the interior of the separating chamber through the top plate 18 and baffle plate 22, while the outer free ends are radially arranged to utilize the centrifugal action in discharging the liquid.

In order to distribute the flow of the liquid substantially uniformly through all parts of the cylinder and thus subject all parts of the body of liquid to the centrifugal action for substantially the same length of time, a series of settling pans or discs 43 are interposed at an intermediate point in the cylinder. The peripheral edges of these pans or discs lie in the layer of mud 41 and each pan is provided with a series of short depending outlet tubes 44, these tubes on alternate pans being located close to the shaft, while those in the other pans are located at a considerably greater radial distance from the shaft. The result of this arrangement is to cause the liquid to flow in a zig-zag path as it travels upwardly toward the outlet tubes 42. It will be noted that each pan 43 has the shape of a cone with a very broad base and a very short axis so that as the liquid mixture flows from an opening 44 adjacent the hollow portion 11 of the shaft to another opening near the peripheral edge of the next pan, it must flow downwardly in opposition to the general direction of flow through the cylinder. The fluid mixture flows upwardly in travelling from one pan to another only as it moves inwardly toward the center of rotation, and consequently travels in opposition to the direction in which it is urged by centrifugal force.

For the purpose of driving the valve mechanism, two brackets 45 and 46, Fig. 1, are mounted on the frame 15 and support a vertical shaft 47, to the lower end of which is secured a pulley 48. A belt 49 connects this pulley with the flanged pulley 34. To the upper end of this vertical shaft 47 is secured a spiral gear 50 meshing with a spiral gear 51 secured on one end of a horizontal shaft 52 mounted in a bracket 53 on the frame 15. Near the end of the shaft 52, remote from the spiral gear 51, is secured a pulley 54 over which passes a belt 55 leading from a pulley 56 on a shaft 57 connected with a suitable source of power. On the shaft 52 between the pulley 54 and the bracket 53 is rotatably mounted a pulley 58, equal in diameter to the diameter of the pulley 54, while secured to the said pulley 58 is a gear 59 which meshes with a gear 60 secured to one end of a shaft 61 rotatably mounted in the upper portion of the bracket 53. At the other end of the shaft 61 is secured a gear 62 meshing with a gear 63 secured on the shaft 52. The gears 60 and 63 are equal in diameter, as are also the

gears 59 and 62, but the gears 59 and 62 are of less diameter than the gears 60 and 63. When the belt 55 therefore is shifted from the pulley 54 to the pulley 58, the combination of gears just described acts as a speed reducing means for the shaft 52.

At the end of the shaft 52 adjacent the pulley 54 is secured a spiral gear 64 which meshes with a spiral gear 65 attached to the upper end of a vertical shaft 66 rotatably mounted in brackets 67 and 68 secured to the frame 15. Attached to the lower end of the shaft 66 is a gear 69 which meshes with gear teeth 70 cut in the periphery of the circular discharge platform 33 and by means of which said platform is rotated. The lower side of the platform 33 near its periphery is provided with a depending ring or track 71, Fig. 4, which rests on a plurality of flanged rolls 72 rotatably mounted on the frame 15.

It will now be understood that the separating chamber is driven at a constant rate of speed by power applied to the pulley 16, while the valve plates 24 and members 28 and 29, may be driven at different rates of speed through the speed change gearing above described. The separating chamber and the valve plates 24 and members 28 and 29 all rotate in the same direction, but the separating chamber rotates at a different speed from the other parts, the valves 25 acting under these conditions to successively uncover and cover the valve ports 21 in the plates 18 and 19. While the ports 21 are uncovered by the valves 25 they will fill with mud, but immediately after the ports are covered again by the valves, each port comes into register with its corresponding slot 30 and the mud pocketed in the valve ports is thrown by centrifugal action through the slots 30 into one of the troughs 31 or 32.

The layer of mud 41, as it builds up on the interior of the cylinder 17, flows endwise of the cylinder toward the top and bottom, through the annular passages between the interior wall of the cylinder and the periphery of the baffle plates 22 and 23 and into the mud chamber so formed between such baffle plates and the top and bottom plates 18 and 19 respectively. To assist such flow and to keep the thickness of the layer of mud 41 as near uniform as possible, I have provided a plurality of rods or wires 73 attached at top and bottom to the ends of the valves 25, as shown in Figs. 3 and 4. These rods or wires exert a leveling action on the layer of mud, accelerate its flow, and prevent caking.

It is desirable to so control the operation of the separator that the mud will be discharged substantially as rapidly as it is deposited. This object may be attained either by varying the rate of deposit or the rate of discharge. I consider it usually more

feasible, however, to control the rate of discharge and for that reason I have provided a governing mechanism for the mud discharging means and I make this mechanism responsive automatically to variations in the thickness of the layer of mud, so that when this thickness increases beyond a predetermined limit the discharging means will be operated to carry the mud away more rapidly, and conversely, if the thickness of the mud layer becomes too greatly reduced, the rate of discharge will be reduced. In other words, the governing mechanism tends to so regulate the rate of discharge of the mud that the thickness of the layer will be maintained within substantially predetermined limits. This governing mechanism is like that shown and described in my co-pending application above designated and reference should be made to this application for a full description of the mechanism. For the present purposes it is merely necessary to say that this mechanism comprises a float or feeler 74, Fig. 4, supported on two pivoted arms 75-75, so that it can move backward and forward in a substantially horizontal plane toward or from the surface of the layer of mud 41. One arm of a bell crank lever 76, fulcrumed at 77, has a pin and slot connection with the rearward end of an extension or arm projecting from the feeler 74, while the other arm of said bell crank lever projects through one of the slots 40 in the hollow portion 11 of the shaft and is pivoted to the lower end of a rod 78 that extends axially through this hollow portion 11 and into the casing 79 mounted on top of the tank 39. A mechanism (not shown) intermittently moves the feeler away from the layer of mud and immediately allows it to return again into contact with the mud so that the position of the feeler during the greater part of the time is determined by the thickness of the wall of mud in the cylinder. This governing mechanism also includes a rack 80 which is moved backward and forward, as indicated by the double arrow, Fig. 6, when the layer of mud becomes too thick or too thin, and this rack is connected by a link 81 to one end of a lever arm 82 that is secured to the upper end of a rock shaft 83 mounted in a bracket 84. To the lower end of this shaft 83 is secured a belt shifting fork 85, which straddles the belt 55 near the pulleys 54 and 58.

The belt 55 is normally in engagement with the pulley 58 so that the valve plates 24 and members 28 and 29 are rotating at such a speed with relation to the speed of rotation of the cylinder as to discharge the accumulated mud through the ports 21 substantially as fast as it is deposited. Should, however, the mud be deposited at such a rate that the valve arrangement comprising the valve covers 25, holes 21 and passages 30

70

75

80

85

90

95

100

105

110

115

120

125

130

be unable to discharge the mud as fast as it is deposited, the feeler 74 will then operate through the governing mechanism to move the rack 80 outwardly, as viewed in Fig. 6, thus causing the belt fork 85 to move the belt 55 off the pulley 58 and on to the pulley 54. The shaft 52 is then connected directly to the driving mechanism and the speed of the valves 25 is changed relatively to the speed of the cylinder to produce a more frequent uncovering of the ports 21 and consequently a more rapid discharge of the mud from the separating chamber.

When the apparatus is first started into operation there will be no mud in the mud chambers, and the valves, therefore, should not be operated until a mud layer has been built up sufficiently to seal the mud chamber. The valve mechanism may then be started and thereafter the apparatus will deliver a substantially constant flow of mud.

The apparatus is enclosed in a sheet metal casing 86 having an interior flange 87, Fig. 4, which cooperates with the top of the casing to form a chamber into which the liquid discharged from the tubes 42 may collect. A discharge nozzle 88 conducts the liquid from said chamber to any convenient point. The mud delivered to the rotating platform 33 is moved therefrom by a stationary scraper 89, Fig. 3, forming one wall of an inclined discharge chute 90 which projects through the side of the casing 86. The momentum of the mud due to the motion imparted to it by the rotating platform 33 carries it through this chute 90. This chute guides the mud to a delivery point where it drops on to a conveyor or into suitable receptacles.

It will now be appreciated that this invention provides a relatively simple form of centrifugal separator in which the solid and liquid constituents of the mixture being treated are automatically separated and discharged from the cylinder, the rate of discharge of the solid material being controlled automatically substantially in accordance with its rate of deposit in the cylinder. The rotary valve mechanism operates smoothly, and since it is always driven in one direction, it avoids the vibration and mechanical difficulties which are very likely to attend the use of reciprocating valves. The chamber in which the separation of the solid and liquid constituents of the mixture takes place, has been above referred to as a cylinder, and the chamber shown is of approximately cylindrical form. It will be understood, however, that the separating chamber does not necessarily have the form of a true cylinder, and that other geometrical forms are regarded as the equivalents of the cylindrical form specifically mentioned.

While I have herein shown and described the best embodiment of the invention of which I am at present aware, it will be appreciated that this embodiment may be modified in many particulars without departing from the spirit or scope of this invention.

What is claimed as new is:

1. A centrifugal separator comprising, in combination, a cylinder, mechanism for rotating said cylinder, means for conducting a mixture of solid and liquid materials to be separated into said cylinder whereby the action of centrifugal force on the mixture will cause the solid constituent of said mixture to separate and form a layer of mud on the inner surface of the cylinder, a discharge outlet for the liquid constituent of said mixture, a plurality of mud discharging ports at the end of the cylinder, and means rotatable relatively to said cylinder for intermittently opening and closing said ports.

2. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a partition cooperating with said cylinder to form a mud chamber in one end thereof, and valve mechanism rotatable relatively to said cylinder for controlling the discharge of mud from said chamber.

3. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a mud collecting chamber in said cylinder, means for acting on the mud in the cylinder to promote its flow into said chamber, and valve mechanism controlling the discharge of mud from said chamber.

4. A centrifugal separator comprising, in combination, a cylinder, mechanism for rotating said cylinder, means for conducting a mixture of solid and liquid materials to be separated into said cylinder whereby the action of centrifugal force on the mixture will cause the solid material a separate and form a layer of mud on the inner surface of the cylinder, a discharge outlet for the liquid constituent of said mixture, a mud chamber at each end of said cylinder, and valve mechanism rotatable relatively to said cylinder for controlling the discharge of mud from said chambers.

5. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, partitions in said cylinder near opposite ends thereof but spaced from said ends to form mud collecting chambers, and valve mechanism rotatable relatively to said cylinder for controlling the discharge of mud from said chambers.

6. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a plurality of circumferentially arranged discharge ports in the end of the cylinder, and means rotatable relatively to said cylinder for intermittently opening and closing said ports to effect the discharge of mud from the cylinder.

7. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a plurality of discharge ports in said cylinder, and valve plates rotatable about the same axis as said cylinder but relatively thereto for intermittently opening and closing said ports to effect the discharge of mud from the cylinder.

8. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a plurality of discharge ports in each end of said cylinder, a plurality of valves cooperating with said ports to effect the discharge of mud from the cylinder, mechanism for rotating said valves concentrically with said cylinder and in the same direction but at a different speed therefrom to intermittently

open and close said ports, and means whereby the rapidity of such openings and closings may be varied.

9. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, mud collecting chambers at the ends of said cylinder, a plurality of discharge ports leading from said collecting chambers to the outside of the cylinder, and valves rotatable relatively to but concentrically with said cylinder for intermittently opening and closing said ports to effect the discharge of mud from the cylinder.

10. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a plurality of mud discharge ports in the end of said cylinder, and rotatable valve means for controlling the discharge of mud through said ports comprising means for covering and uncovering both the inner and outer ends of said ports.

11. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a plurality of mud discharge ports in each end of said cylinder, rotary valve mechanism for controlling the discharge of mud through each set of ports, means for driving the valve mechanism at one end of said cylinder, and connections extending through the cylinder for driving the valve mechanism at the opposite end of the cylinder.

12. A centrifugal separator comprising, in combination, a cylinder, means for rotating said cylinder, means for conducting a mixture of solid and liquid materials to be separated into said cylinder whereby the action of centrifugal force on the mixture will separate the solid and liquid constituents thereof, a discharge outlet for said liquid constituent, said cylinder having a series of mud discharging ports formed

therein, a valve plate within said cylinder to open and close the inner ends of said ports, another plate external to said cylinder constructed to cover the outer ends of 5 said ports while the inner ends thereof are open and to uncover the outer ends of said ports after the inner ends thereof have been closed by said valve plate, and mechanism for rotating said plates relatively to said 10 cylinder.

13. A centrifugal separator comprising, in combination, a cylinder, means for rotating said cylinder, means for conducting a mixture of solid and liquid materials to 15 be separated into said cylinder whereby the action of centrifugal force on the mixture will separate the solid and liquid constituents thereof, said cylinder having a series of mud discharging ports in the end thereof, a valve plate mounted in contact with the inner face of said end and constructed to open and close the inner ends of said ports, another plate in contact with the outer face of said end of the cylinder to cover 20 the outer ends of said ports when said valve plate opens the inner ends thereof, and vice versa, said plates being mounted to rotate about the axis of rotation of said cylinder, and gear mechanism for rotating said plates 25 in unison in the same direction as but at a different speed from said cylinder.

14. A centrifugal separator comprising, in combination, a cylinder, means for rotating said cylinder, means for conducting a mixture of solid and liquid materials to 30 be separated into said cylinder whereby the action of centrifugal force on the mixture will separate the solid and liquid constituents thereof, said cylinder having a series of mud discharging ports in each end thereof, valve mechanism controlling the discharge of mud through said ports and comprising an internal and an external plate at each end of the cylinder, said plates being 35 mounted to rotate about the axis of said cylinder, means for driving one of said external plates, and connections including shafts projecting through said cylinder for driving the other plates from said driven 40 plate and in unison therewith.

15. A centrifugal separator comprising, in combination, a cylinder, means for rotating said cylinder, means for conducting a mixture of solid and liquid materials to be separated into said cylinder whereby the action 45 of centrifugal force on the mixture will separate the solid and liquid constituents thereof, said cylinder having a series of mud discharging ports in each end thereof, valve mechanism controlling the discharge of mud 50 through said ports and comprising an internal and an external plate at each end of the cylinder, said plates being mounted to rotate about the axis of said cylinder, mechanism 55 for rotating said plates in unison in the same

direction as but at a different speed from the cylinder, and a plurality of mud distributing rods located within said cylinder closely adjacent to the inner wall thereof and supported by said internal plates at the opposite ends of said cylinder. 70

16. A centrifugal separator comprising, in combination, a cylinder, mechanism for rotating said cylinder, means for conducting a mixture of solid and liquid materials to 75 be separated into said cylinder whereby the action of centrifugal force on the mixture will cause the solid material to separate and form a layer of mud on the inner surface of the cylinder, a discharge outlet for the liquid constituent of said mixture, a plurality of mud discharge ports in the end of said cylinder, rotary valve mechanism for opening and closing said ports to control the discharge of mud therethrough, and means 80 responsive automatically to variations in the thickness of said layer of mud for controlling the rate of discharge of the mud from the cylinder through said ports. 85

17. A centrifugal separator comprising, in combination, a cylinder, mechanism for rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a plurality of mud discharge ports in said cylinder, a 90 plurality of valves cooperating with said ports to control the discharge of mud from the cylinder, means for rotating said valves concentrically with said cylinder in the same direction but at a different speed therefrom to intermittently open and close said ports, and means whereby the rapidity of such openings and closings may be varied. 95

18. A centrifugal separator comprising, in combination, a cylinder, mechanism for 100 rotating said cylinder, means for conducting a mixture of solid and liquid materials to be separated into said cylinder whereby the action of centrifugal force on the mixture will cause the solid material to separate and form a layer of mud on the inner surface of the cylinder, a discharge outlet for the liquid constituent of said mixture, a plurality of discharge ports in the cylinder, 105 valves cooperating with said ports to control the discharge of mud from the cylinder, mechanism for rotating said valves relatively to said cylinder, said valve rotating means including a reduction gearing, and means 110 responsive to variations in the thickness of said layer of mud for automatically throwing said reduction gearing into and out of connection with said valve rotating means to change the speed of rotation of said valves. 115

19. In a centrifugal separator arranged to receive continuously and separate substances of varying density, the combination with the receiving cylinder and its end plate, of a 5 baffle plate forming a narrow chamber between said baffle plate and end plate open to the main chamber of the cylinder near the periphery thereof, valve openings in said end plate, a rotating valve plate between 10 said baffle plate and end plate having its axis concentric with the axis of rotation of the cylinder and also having valve arms, an exterior rotating valve plate for said valve openings arranged to close said valve openings 15 in the end plate exteriorly when open interiorly, and open them exteriorly when closed interiorly, and means to rotate said valve plates in unison but at a speed variable with reference to the speed of rotation 20 of the cylinder.

20. A centrifugal separator comprising,

in combination, a cylinder, mechanism for rotating said cylinder, means for conducting a mixture of solid and liquid materials to be separated into said cylinder whereby 25 the action of centrifugal force on the mixture will cause the solid material to separate and form a layer of mud on the inner surface of the cylinder, a discharge outlet for the liquid constituent of said mixture, a 30 plurality of mud discharge ports in said cylinder, a plurality of valves cooperating with said ports to control the discharge of mud from the cylinder, means for rotating said valves concentrically with said cylinder 35 in the same direction but at a different speed therefrom to intermittently open and close said ports, and means responsive to changes in the thickness of said layer of mud for automatically changing the speed 40 of rotation of said valves.

JAMES MACKAYE.
